UNITED STATES PATENT OFFICE.

LOUIS MEYER, OF NEW YORK, N. Y.

PRINTING-PRESS.

1,359,720.

Specification of Letters Patent. Patented Nov. 23, 1920.

Application filed February 27, 1920. Serial No. 361,764.

To all whom it may concern:

Be it known that I, LOUIS MEYER, a citizen of the United States, and a resident of the city of New York, county of Bronx, and

5 State of New York, have invented a new and Improved Printing-Press, of which the following is a full, clear, and exact description.

10 My invention relates to a printing press particularly adapted for printing on continuous ribbons or tapes.

An object of the invention is to provide a simple, inexpensive and efficient printing press, whereby sections of ribbon or tape of 15 different lengths and widths can be printed simultaneously on the press.

Another object of the invention is to provide a press so arranged, that the result of the printing on the ribbon is at all times before the operator of the press, and does not require the stopping of the press for the purpose of inspecting the work.

With these and other objects in view, the nature of which will more fully appear as 25 the description herein proceeds, the invention consists in the novel construction, combination, and arrangement of parts as herein fully described, illustrated and claimed.

In the accompanying drawings, forming 30 part of the application, similar characters of reference indicate corresponding parts in all the views.

Figure 1 represents a side elevation of a printing press, embodying a preferred form 35 of my invention and in which the operating handle is removed to better illustrate the invention.

Fig. 2 is a side elevation of the gravitationally operated cams, showing the same in the 40 position when the rocking arm passes under the cam. Fig. 2^a is a plan of the cam showing the extensible part of same.

Fig. 3 is a side elevation of the rocker arm with the jaw, showing the jaw down, that is, 45 when the ribbons are gripped to be fed.

Fig. 4 is a top plan view of the printing press.

Fig. 5 is a vertical section on line 5—5, Fig. 6.

50 Fig. 6 is a vertical section on line 6—6, Fig. 5, certain parts in said figure being shown diagrammatically.

Referring to the drawings, 7 is the frame, in which the supporting drum 8 is mounted 55 to revolve. The frame 7 also carries pairs of rollers 9 at the front and rear ends of the

frame. A bed 10 is mounted on the pairs of rollers 9 so that it also rests on the drum 8; the said drum 8 being adapted to take up the pressure which is applied to the bed. A 60 type carrying plate 11 is mounted on the bed 10, suitable means being provided on the bed and plate for securing one to the other.

The frame 7 has uprights 12 which receive the bearings of the D roller 13. The bearings 14 of the D roller are mounted slideably in the uprights, and the direction of the sliding motion of said bearings is in a plane passing through the axis of the D roller and the drum 8. In consequence, the pressure 70 applied by the D roller to the bed 10 is taken up by the drum 8. The D roller is actuated by means of arms 15 disposed to one side of the frame as best shown in Fig. 4.

The frame 7 supports a receptacle 16 at 75 the rear end of same adapted to carry the rollers of tape 17 which are to be printed upon. The ends of the ribbons of the rolls located in the receptacle 16 are passed over a roller 18, revolubly mounted in a frame 80 19, which is attached to the uprights 12 of the frame 7 and extends rearwardly of the press. From the roller 18 the tape passes over a wooden brace 20, which is secured to the frame 19. This brace 20 is adapted to 85 receive pins 21, which provide the desired spacing between the rows of ribbons to be printed upon. (See Fig. 4.) The ribbons then pass over the D roller. From the D roller the tapes are threaded through a 90 gripping device 22, and from there over a roller 23, which revolves continuously in the frame 19 in the direction indicated by the arrow in Fig. 1. The means for revolving the roller 23 are not shown in the drawings. 95

The gripping device 22 is mounted to slide in the frame 19, the sliding motion being imparted thereto by the bed 10 through the medium of a first-class lever 24 which is connected to the gripping device by links 110 25, said lever 24 being fulcrumed on the frame 19; (see Figs. 1 and 6), the shorter arm 26 of said lever 24 being engaged between two pins 27 adjustably mounted in a plate 28 which is rigidly secured to the bed 10. By varying the relative position of the pins 27 it is possible to vary the stroke of the bed 10, in consequence, varying the quantity of slack of tape 17 through the medium of the extension 29 of the bed 10. 110

The frame 30 of the gripping device 22 carries two alining shafts 31, each provided

at its outward extremity with a rocker arm 32; the ends of the arms 32 being provided with rolling pins 33, each adapted to engage a corresponding cam track 34 which is 5 hinged at 35 to the frame 19. The track 34 has a portion 36 adjustably mounted thereon (see Fig. 2^a) whereby the operative length of the track may be varied.

Each of the shafts 31 carries a jaw 37 10 constrained to move with its shaft 31 and rocker arm 32. The jaws 37 are maintained against their corresponding stops 38, by a corresponding spring 39. The movement of the jaws 37 toward the bottom 40 15 of the frame 30 is produced by the cam tracks 34 when the roller pins 33 of the rocker arms are operatively engaged therewith.

The bottom 40 of the frame 30 is preferably provided with a groove 41, adapted to 20 receive the ends of the jaws 37 and bind the tape between the bottom and the jaws, and thereby prevent the tape from slipping when the gripping device is moved rearwardly by the motion of the lever 24.

By varying the operative length of the cam tracks 34, the amount of tape fed is varied accordingly, although the jaws 37 will always engage the tape at the time the 30 roller pins 33 reach the top of the track, 34. (See Fig. 3). The length of the time during which the engagement is maintained between the jaws and tape depends on the length of the tracks, which as previously 35 stated, are adjustable.

As the gripping device 22 slides forward the rocker arms 32 will ride under the cam track 34 (see Fig. 2) and raise the said track 34 when passing the cam ends of 40 same, and allowing the said track to drop to the original position onto the frame 19, to be in a position to engage the rolling pins 33 of the rocker arms 32, when the gripping device moves rearward. The engagement of the jaws 37 with the bottom 40 of 45 the frame 30 is best illustrated in Fig. 3.

The bottom 40 of the frame 30 carries a wooden bar 42 into which pins 43 may be placed to maintain the desired spacing between 50 the rows of tapes, as best shown in Fig. 4. The ends of the jaws are provided with slits 44 to make the ends of the jaws more flexible and to increase the gripping effect of the jaws upon the tapes. This arrangement also permits the proper gripping by the device of tapes of different thicknesses.

By providing independently operable jaws 39, with the corresponding cam tracks, it is 60 possible by making one of the cam tracks longer, to print simultaneously rolls of shorter and longer tapes, the rolls of longer tape being printed upon when the track is longer, for the gripping device operating 65 from the longer track will debit greater

lengths of tape sections. It may be here remarked that the extension 29 of the bed is only to provide sufficient slack for the gripping device, and that slack is always slightly in excess of what the maximum 70 debit of the gripping device may be.

As the D roller is revolved to bring the tape into engagement with the type carrying plate 11, the bed is moved rearward by the engagement of the arm 45 with the projection 46 of the bed, the gripping device slides forwardly without engaging the tape. The movement of the bed rearwardly produces slack in the tape 17, by pulling it from the rollers carried in the receptacle 80 16. It cannot pull on the tape located above the bed for a part of it is pressed by the D roller against the type. As the D roller is returned to its initial position, the bed is moved forwardly by the weight 45 85 and causes the gripping device to slide rearwardly which brings the rocker arms into engagement with the cam tracks forcing the jaws of the gripping device to engage the tapes and pull the same rearwardly over the 90 D roller, thereby bringing the sections of the tapes printed upon into the vision of the operator, so that he can see the character of the work. The tapes fed by the gripping device are taken up continuously by the rotation of the roller 23, the friction between the tape and the roller being sufficient to maintain the tapes between the D roller and the said roller 23 taut.

I claim:

1. In a printing press of the class described, a bed mounted to reciprocate, a tape gripping device also mounted to reciprocate above the bed, a first class lever connecting the said bed and gripping device, means associated with the bed for forming slack in the tape, and means for operating the gripping device while the gripping device moves in a predetermined direction rearwardly.

2. In a printing press of the class described, a bed mounted to reciprocate, a tape feeding device also mounted to reciprocate above the bed, means connecting the feeding device to the bed to impart the reciprocating motion of the bed to the feeding device, means for producing slack in the tape associated with the bed, and means for rendering the feeding device operative during a predetermined part of its reciprocating motion.

3. In a printing press of the class described, a bed mounted to reciprocate, a tape feeding device also mounted to reciprocate, a first class lever interposed between the table and the gripping device for transmitting the reciprocating motion of the bed to the gripping device, slack forming means for the tape associated with the bed, and means for operating the gripping device

while the same moves in a predetermined direction.

4. In a printing press of the class described, a tape feeding device comprising a frame mounted to reciprocate, means for reciprocating the said frame, spring actuated jaws in said frame tending to remain open, a rocker arm associated with each jaw, a gravitationally operable extensible cam track for each of the rocker arms, and means associated with said tracks for operatively engaging the said rocker arms when the feeding device moves in a predetermined direction.

15 5. In a printing press of the class described, a tape feeding device comprising a frame mounted to reciprocate, spring actuated jaws in said frame normally tending to remain open, a rocker arm for each jaw, a gravitationally operable cam track for each of the arms for engaging the said arms when the frame reciprocates into a predetermined direction, whereby the jaws are closed.

25 6. In a printing press of the class described, a bed mounted to reciprocate, a tape feeding device mounted to reciprocate above the bed, a first class lever for transmitting the reciprocating motion from the bed to the

feeding device, means carried by the bed for producing slack in the tape, spring actuated jaws in the tape feeding device normally tending to remain open, the said jaws being adapted to receive the tape to be printed upon therebetween, a rocker arm for each of the jaws, a gravitationally operable extensible cam track for each of the arms, said cam tracks being adapted to engage the said rocker arms when the feeding device is reciprocated into a predetermined direction, whereby the jaws are closed and the tape is fed by the feeding device, and a revolute member adapted to take up the slack caused to the tape by the feeding device.

7. In a printing press of the class described, a tape feeding device comprising a frame mounted to reciprocate, two alining shafts revolubly mounted in said frame, a jaw for each of the shafts, a spring for each jaw normally maintaining the same in a raised position, a rocker arm for each of the shafts constrained to move therewith, an extensible track for each of the rocker arms, and means associated with each of the tracks to operably engage the corresponding rocker arm when the frame is reciprocated into a predetermined direction.

LOUIS MEYER.
